UNITED STATES PATENT OFFICE

FREDERICK S. ANABLE, OF BOSTON, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE

1,168,777.

Specification of Letters Patent. Patented Jan. 18, 1916.

Application filed February 1, 1908. Serial No. 413,798.

To all whom it may concern:

Be it known that I, FREDERICK S. ANABLE, a citizen of the United States, residing at Boston, in the county of Suffolk and State 5 of Massachusetts, have invented an Improvement in Strip-Serving Devices, of which the following description, in connection with the accompanying drawings, is a specification, like letters on the drawings 10 representing like parts.

This invention relates to devices or apparatus for supplying strips of paper or other suitable material of any desired length to be applied to packages, bottles, bundles or 15 the like as a wrapping means or as a label or for any other desired purpose, the illustrated embodiment of the invention showing an apparatus provided with means for holding a strip supply previously gummed on one 20 side, such strip being adapted to be withdrawn in selected lengths and further provided with means for moistening the gummed side of the strip as the latter is withdrawn. It is apparent that an ungummed strip of 25 paper or the like might be employed, and the moistening device be utilized for applying adhesive to the side of the withdrawn strip.

My invention will be best understood by 30 reference to the following description when taken in connection with the accompanying illustration of one specific embodiment thereof, the scope of the invention being more particularly pointed out in the appended claims.

Referring to the drawings,—Figure 1 is a side elevation of a strip serving device embodying one form of my invention; Fig. 2 is an elevation, partly in section, upon the 40 line 2—2 of Fig. 1 and looking toward the right in said figure; Fig. 3 is a plan view of a portion of the apparatus shown in Fig. 1.

In the several forms of the invention 45 herein disclosed, various means are provided to prevent contact of the free end of the strip with the moistener when the apparatus is not in use.

Referring first to the form of the invention shown in Figs. 1, 2 and 3, the strip support therein indicated at 1 may be of any suitable character. Preferably, the strip is supported in the form of a roll in a suitable 50 casing upon a base 2, there being provided

suitable tensioning means for the roll, as, 55 for example, a thumb nut 3. Preferably mounted upon the base 2 is a tank or reservoir 4 having operatively connected thereto any suitable moistening device, herein represented as a wick 5 arranged in inverted 60 U-shape with the ends thereof depending into the tank, the intermediate portion being suitably disposed to moisten the strip as the latter is drawn across the same. Any suitable strip severing means may be provided, 65 as, for example, a blade 6, herein represented as in advance of the moistener. I contemplate the provision of a shield or cover adapted to be interposed between the moistener and the strip, such shield normally or when the apparatus is not in use 70 being interposed between the free end of the strip and the moistener. In such event, therefore, a stationary moistener may be employed, and I need not provide means tending normally to separate the moistener and the strip. It is apparent that the shield or 75 cover may be interposed in any suitable manner between the strip and the moistener. Preferably, however, I provide means 80 whereby, upon draft upon the strip for use, the shield or cover is withdrawn from the moistener. In that specific form of the invention shown in said figures, I have provided a cover formed in two parts 85 7 and 8 (see Fig. 3) mounted for lateral movement toward and from each other. Preferably guides 9 and 10 are formed upon the rear and front of the reservoir to receive the depending edges of the 90 cover and guide the same. Rearwardly extending from the rear depending portions of the cover numbers are rods 11 and 12 adapted to receive between them a wedge or plunger 13 having a guiding member 14 95 that may be received within a socket in the base 2. Normally the wedge or plunger 13 is held elevated by a coil spring 15 interposed between a cross bar 16 upon the upper end of the plunger and a guide strip 17 100 mounted in brackets 18 rearwardly extending from the reservoir. When the strip is not drawn upon for use, the elevated plunger maintains the strip in the form of a bight, guiding rolls 19 and 20 being preferably provided in the rear and in advance 105 of the plunger. The free end of the strip may rest directly upon the shield or cover,

as represented in Fig. 1. When the free end of the strip is drawn upon for use, the plunger is depressed, the wedge portion 13 thereof acting to separate or slide laterally the cover members 7 and 8 thereby immediately exposing the moistener for use. When a suitable length of strip has been drawn, it is severed by a suitable movement of the hand of the operator, whereupon the 10 spring 15 at once elevates the plunger. A spring 21 or other suitable device is employed to return the cover members to closed position.

Having thus described my invention, I 15 desire it to be understood that although specific terms are employed, they are used in a descriptive and generic sense and not for purposes of limitation, the scope of the invention being set forth in the following 20 claims.

Claims:

1. A strip serving device comprising in combination a strip support, means to render the strip adhesive, a movable inclosure 25 for said means adapted to intervene between the strip and said means to prevent contact of the strip and said means, and means controlled by draft upon the strip to move said inclosure, thereby to expose for operation 30 said means to render the strip adhesive.

2. A strip serving device comprising in combination, a strip support, a strip moistener, a movable shield for the moistener, and means controlled by the strip to move 35 said shield, thereby to expose the moistener.

3. A strip serving device comprising in combination, a strip support, a strip moistener, a shield movable transversely of the moistening face of the moistener, and means 40 controlled by draft upon the strip to move said shield, thereby to expose the moistener.

4. A strip serving device comprising a strip support, a bodily stationary moistener in operative relation thereto, and movable 45 means between the strip and moistener to expose the moistener for use upon delivery of material from said support, said means being movable into moistener exposing and non-exposing positions by movement of the 50 strip in its true service path.

5. A strip serving device comprising in combination a strip support, a strip moistener, and means controlled by non-deflecting draft upon the free end of the strip for 55 use to uncover the moistener, thereby avoiding the necessity of deflection of the free end of the strip from its service path.

6. A strip serving device comprising in combination a strip support, a stationary 60 strip moistener, and means controlled by non-deflecting draft upon the free end of the strip for use to uncover the moistener.

7. A strip serving device comprising a strip support, a bodily stationary moistener 65 in operative relation thereto, and movable

means controlled by non-deflecting draft upon the free end of the strip for use to uncover the moistener.

8. A strip serving device comprising in combination a strip support, a stationary 70 moistener, and movable means controlled by non-deflecting draft upon the free end of the strip to expose the moistener for use.

9. A strip serving device comprising in combination, a strip support, a stationary 75 moistener, and means controlled by non-deflecting draft upon the free end of the strip to shield and unshield the moistener.

10. A strip serving device comprising in combination a strip support, a stationary 80 moistener, and means controlled by non-deflecting draft upon the free end of the strip to uncover the moistener and active upon release of the strip to cover the moistener.

11. A strip serving device comprising a 85 strip support, a moistener in operative relation thereto, strip shielding means between the strip and moistener, normally movable into operative and inoperative positions and means to move the same from between the strip and moistener into inoperative position.

12. A strip serving device comprising a strip support, a moistener in operative relation thereto, strip shielding means between the strip and the moistener, means to move the same from between the strip and the moistener into non-shielding position upon delivery of the strip for use, and means to return the same into shielding position between the strip and moistener upon the termination of the strip serving operation.

13. A strip serving device comprising a strip support, a bodily stationary moistener, and means active with the strip in substantially its true service path to shield the strip from the moistener at the termination of the serving operation.

14. A strip serving device comprising a strip support, a stationary moistener in operative relation thereto, and means active with the strip in substantially its true service path to shield the strip from the said moistener at the termination of the serving operation.

15. A strip serving device comprising a strip support, a moistener in operative relation thereto, a cover for the moistener adapted to be positioned between the strip and moistener, and means to withdraw the cover from between the strip and moistener during the strip serving operation.

16. A strip serving device comprising a strip support, a moistener in operative relation thereto, a laterally movable cover for the moistener adapted to be positioned between the strip and moistener, and means to withdraw the cover from such position during the strip serving operation.

17. A strip serving device comprising a

strip support, a moistener in operative relation thereto, a cover for the moistener, and a movable member operatively connected to said cover and adapted to be moved by draft upon the strip for use to withdraw the cover from between the free end of the strip and the moistener.

18. A strip serving device comprising a strip support, a moistener in operative relation thereto, a cover for the moistener and a plunger operatively connected to the cover and adapted to be moved by draft upon the strip for use to withdraw the cover.

19. A strip serving device comprising a strip support, a moistener in operative relation thereto, a cover for the moistener, a movable member structurally distinct from but operatively connected to the cover and adapted to be moved by draft upon the strip for use to uncover the moistener, and a spring to return said member.

20. A strip serving device comprising a strip support, a moistener in operative relation thereto, and a sliding cover for the moistener adapted to be positioned between the strip and moistener, and means to withdraw the cover from such position during the strip serving operation.

21. A strip serving device comprising a strip support, a moistener in operative relation thereto and a cover for the moistener adapted to be positioned between the strip and moistener and laterally movable relative to the strip, means so to move the cover during the strip serving operation, and means to return the cover to its operative position.

22. A strip serving device comprising a strip support, a moistener in operative relation thereto, a closure for said moistener interposed between the same and said strip, and means rendered operative by draft upon the strip for use to move said closure in the path of travel of the strip, and thereby render the moistener operative.

23. A strip serving device comprising a strip support, a moistener in operative relation thereto, a closure for said moistener interposed between the same and said strip, means rendered operative by draft upon the strip for use to move said closure in the path of travel of the strip, and thereby to render the moistener operative, and means to restore the closure to its operative position.

24. A strip serving device comprising in combination, a strip support, a strip moistener, moistener covering means, and means controlled by non-deflecting draft upon the free end of the strip for use to expose the moistener.

25. A strip serving device comprising in combination, a strip support, a strip moistener, a device adapted directly to intervene between the moistener and the strip in its service path and controlled as to its position by draft upon the strip and release of the strip, respectively.

In testimony whereof, I have signed my name to this specification, in the presence of two subscribing witnesses.

FREDERICK S. ANABLE.
